UNITED STATES PATENT OFFICE.

HENRY NOGRADY, OF DETROIT, MICHIGAN, ASSIGNOR OF ONE-HALF TO ALEXANDER WEISS, OF FORDSON, MICHIGAN.

MULTIPLE-YEAR CALENDAR.

Application filed July 25, 1927. Serial No. 208,282.

This invention relates to multiple year calendars and has as an object to provide an improved form of such a calendar which can be readily used by any one without detailed or intricate instructions as to its use.

Another feature of the calendar of this invention is that it shows the entire calendar month at one setting for the month and year desired, and also shows on its face the month 10 and year for which it is set.

Another feature is that the year ordinals are arranged in numerical order to facilitate the ready finding of the desired year ordinal to permit quick setting of the calendar for 15 any year shown thereon.

Another feature is the provision for showing correctly the entire calendar months for leap years without any special calculations or corrections to be made by the user.

20 Another feature of this invention is that a four hundred year calendar made according to this invention will not be of excessive size, and since our calendar repeats itself every four hundred years, such a calendar 25 will in fact be a perpetual calendar.

Another feature is that with such a perpetual calendar any month for any year far in the past or far in the future can be readily and quickly shown.

30 Another feature is the simplicity and economy of manufacture of calendars made according to the principles of this invention.

Further objects and advantages of the present invention will be apparent from the 35 following description, reference being had to the accompanying drawings, wherein a preferred form of embodiment of the present invention is clearly shown.

In the drawings:

40 Fig. 1 is a view of the rear disk of a calendar for the years 1920 to 1942 inclusive.

Fig. 2 is a front view of the calendar, that is, with the front disk pivoted upon the rear disk of Fig. 1 and disclosing through 45 two arcuate cut-away portions of said front disk certain portions of the rear disk.

Fig. 3 is a view of the rear disk of a four hundred year calendar made according to this invention, to be used as a perpetual calendar simply by adding 400 or multiples of 50 400 to the year ordinals shown when setting the calendar for any year of any century.

Fig. 4 is a front view of the perpetual calendar, that is, with the front disk pivoted upon the rear disk of Fig. 3 and disclosing

through a cut-away portion at the top seven radial columns of year ordinals on the rear disk, and through a cut-away portion near the bottom a calendar month of 31 days properly arranged in weeks on the rear disk. 60

Referring to the drawings, *a* designates the rear disk of the calendar of Figs. 1 and 2 and *b* the front disk shown in Fig. 2. Disk *a* is divided by radial lines *c* into a number of equal sectors which is a multiple of seven, in 65 this particular case, 28 sectors. These 28 sectors are divided into groups of seven each by the points *d*, and four conunterclockwise spiral lines *e* begin at these four points *d* and extend with an equal pitch around the 70 disk from the inner circle *f* to the outer circle *g*. It is clear that the radials *c* and the spirals *e* will intersect to divide the annular area *h* between circles *f* and *g* into four 75 spiral rows of blocks. It will also be clear that if numerals from 1 to 31 be placed on each spiral row of blocks beginning with the inside blocks adjacent the four points *d* and running counterlockwise the numerals in any single radial column of these blocks will 80 increase by 7 from the inside to the outside block, for instance the radial column adjacent any one of the four points *d* will be 1, 8, 15, 22, 29 and the next adjacent column will be 2, 9, 16, 23, 30, etc. It will now also 85 be clear that any mutually adjacent seven of these radial columns will properly represent a calendar month of 31 days properly divided into weeks and beginnig on any day of the week depending upon which column 90 the numeral 1 appears in.

On the peripheral margin of disk *a* outside the circle *g* the year ordinals are applied one ordinal to each sector running in numerical order in a clockwise direction but 95 with a blank sector immediately preceding each leap year ordinal. In this particular case the ordinals of years from 1920 to 1942 inclusive are used and it will be noted that the leap years 1924, 1928, 1932, 1936 and 1940 100 have blank sectors immediately preceding them. The leap year ordinal 1920 is the starting point and hence it is not necessary to have a blank sector immediately prior thereto. 105

Now the front disk *b* is pivotally mounted coaxially upon the rear disk *a* by any suitable pivot means such as the small metal tubular rivet *j* (see Fig. 2). This disk *b* has an arcuate cut-out portion or hole *k* of 110

such dimensions and so located as to expose at one setting thereof seven mutually adjacent radial columns of the days of the month ordinals on disks *a*, and hence there will 5 always be exposed at one time a month calendar of 31 days properly divided into weeks and beginning on any desired day of the week depending upon the setting of disk *b* upon disk *a*, this necessarily being true due 10 to the construction of disk *a* as hereinabove described.

Now the remaining problem in constructing the calendar is to provide index means on disk *b* having a certain relation to any 15 certain year ordinal on disk *a* whereby disk *b* can be properly set for any desired month of any desired year ordinal and cause hole *k* to expose the correct monthly calendar for the desired month and year. This problem 20 can be solved in the following manner:

We know that January 1st for the year 1922 fell on Sunday. We also know the following to be always true for normal years (not leap years):

25 Feb. 1st always falls on same day of week as Jan. 4th.

Mar. 1st always falls on same day of week as Feb. 1st or Jan. 4th.

30 Apr. 1st always falls on same day of week as Mar. 4th or Jan. 7th.

May 1st always falls on same day of week as Apr. 3rd or Jan. 9th or Jan. 2nd.

June 1st always falls on same day of week as May 4th or Jan. 5th.

35 July 1st always falls on same day of week as June 3rd or Jan. 7th.

Aug. 1st always falls on same day of week as July 4th or Jan. 10th or Jan. 3rd.

Sept. 1st always falls on same day of week 40 as Aug. 4th or Jan. 6th.

Oct. 1st always falls on same day of week as Sept. 3rd or Jan. 8th or Jan. 1st.

Nov. 1st always falls on same day of week as Oct. 4th or Jan. 4th.

45 Dec. 1st always falls on same day of week as Nov. 3rd or Jan. 6th.

Jan. 1st of succeeding year falls on same day as Dec. 4th or Jan. 9th or Jan. 2nd.

We now set disk *b* so that the exposed calendar month begins on Sunday, and then 50 mark the index "Jan." on disk *b* to register with the ordinal 1922 on the rear disk *a*. The disk *b* has an arcuate hole *m* cut therein to expose the peripheral margin of seven

55 sectors on the rear disk *a*, as clearly shown in Fig. 2, and seven corresponding sectors laid off on disk *b* with the index "Jan." on the sector to the right. From the above table we learn that Feb. 1, 1922 began on 60 same day as Jan. 4th, or Wednesday. We therefore mark the index "Feb." on disk *b* in the fourth sector to the left, counting as the first sector that marked with the index "Jan." It will be readily seen that if index 65 "Feb." be turned clockwise to register with

the ordinal 1922, the calendar month will then begin on Wednesday, which will be correct. The above table also informs us that March 1st falls on same day as Feb. 1st; hence index "Mar." is placed in same sector 70 with "Feb." April 1st falls on same day as Jan. 7th; hence index "Apr." is placed on seventh sector to the left. May 1st falls on same day as Jan. 2nd; hence index "May" is placed on second sector. June 1st falls 75 on same day as Jan. 5th; hence index "June" is placed on fifth sector. July 1st falls on same day as Jan. 7th; hence index "July" is placed on seventh sector with "Apr.". August 1st falls on same day as Jan. 3rd; hence index "Aug." is placed on third sector. Sept. 1st falls on same day as Jan. 6th; hence index "Sept." is placed on the sixth sector. Oct. 1st falls on same day as Jan. 1st; hence index "Oct." is placed on first 85 sector with "Jan.". Nov. 1st falls on same day as Jan. 4th; hence index "Nov." is placed on fourth sector with "Feb." and "Mar.". Dec. 1st falls on same day as Jan. 6th; hence index "Dec." is placed on sixth sector 90 with "Sept.".

It will now be clear that if the index for any month on disk *b* be turned opposite the ordinal 1922 on the disk *a* the hole *k* in the disk *b* will expose a calendar month beginning on the correct day of the week. For the proper use of the calendar then, it is only necessary to remember that Feb., Apr., June, Sept., and Nov. do not have 31 days.

The above table also shows (as every one 100 knows) that in normal years Jan. 1st of the next succeeding year falls on same day as Jan. 2nd of the instant year. Therefor Jan. 1st, 1923 falls on Monday. Now since the ordinal 1923 is placed in the next sector to the right of ordinal 1922, it will be clear that if the index "Jan." be set to register with ordinal 1923 the exposed calendar month will begin on Monday, which will be correct for January, 1923. From the above 105 explanation of the arrangement of the monthly indexes on disk *b* it must follow that if January is correct all the remaining months must also be correct when their indexes are set to register with the ordinal 1923. And so the calendar operates in this manner for all other normal years (not leap years).

However a correction must be made in the 110 operation of the calendar to take care of the extra day in February of leap year. As previously described, each leap year ordinal has a blank sector immediately preceding it. Take, for instance, the leap year 1924. A blank sector lies between the ordinals for 115 1923 and 1924. Therefore if the index "Jan." be set to register with 1924, January 1st will be moved two days later in the week over January 1st, 1923 and will fall on 120 Wednesday, instead of Tuesday, as it should. 125

Consequently February 1st, if the indexes be used in the ordinary manner, will also be moved two days later in the week over February 1st, 1923, and will therefore be incorrect. However, since the extra day of the leap year occurs before March 1st, when the index "Mar" is set opposite the ordinal "1924" March 1st will fall two days later in the week over March 1st, 1923, and will be correct. Also all the remaining months of the year will be correct when their indexes are used in the ordinary manner.

Now to correct for the leap year error in the two months of January and February, these two months are given special indexes to be used only during leap years, while their normal indexes are to be used during all normal years as previously described. In Fig. 2 the special index for January is marked JAN and is placed in the seventh sector with indexes "Apr." and "July". It will be obvious that when this special index for January is used the month will begin a day earlier in the week than when the normal index is used, thereby making the calendar correct for the month of January during a leap year. Similarly the special index for February is marked FEB and is placed in the third sector instead of in the fourth, thereby correcting for the blank sector preceding the leap year ordinals on disk *a* during a leap year. Preferably these special indexes for January and February are peculiarly marked corresponding to the marking of the leap year ordinals, whereby the marking itself will suggest that these special indexes be used during leap years. For instance, these special indexes may have a distinctive form of lettering, or coloring, or shading, corresponding to that of the leap year ordinals while the remaining ordinals and indexes are plain or non-distinctive. In Figs. 1 and 2, the leap year ordinals on disk *a* have simply been underlined corresponding to the underlining of the special indexes for January and February.

The calendar shown in Figs. 1 and 2 is for the years 1920 to 1942 inclusive. Obviously the principles of this invention can be readily used for making a calendar for any other similar period of years, or for a much longer or even shorter period of years. All the instructions necessary for the use of this calendar is as follows: Set the desired month opposite the desired year during normal years, while in leap years use the special indexes for the months of January and February. For example, the setting of the calendar in Fig. 2 is correct for the month of February, 1920, since the special index is set to register with the leap year ordinal 1920.

Figs. 3 and 4 show a four hundred year calendar, usable as a perpetual calendar,

made according to the principles of this invention. In this modification, the rear disk *A* is divided into 126 equal sectors, which are divided by the points *D* into 18 groups of seven each, instead of into only four groups as in Fig. 1. Spiral lines *E* are laid off beginning at points *D* and extending with such pitch that six of these spirals *E* overlap for the distance of the width of three sectors, thereby providing five overlapping spiral rows of blocks for the numerals 1 to 31. These numerals are applied in the same relation as hereinabove described for Fig. 1, namely, the numerals are so arranged in the spiral rows and radial columns that any mutually adjacent seven of the radial columns will properly represent a calendar month of 31 days properly divided into weeks and beginning on any day of the week depending upon which column the numeral 1 appears in.

The annular area outside the circle *G* on disk *A* is divided into four circular rows of 126 spaces each since there are 126 radial sectors. Now beginning with the year 1 the year ordinals from 1 to 100 are applied to the spaces on the inside row, leaving a blank space preceding each of the 24 leap years. Therefore the ordinals from 1 to 100 lack only two spaces of completely filling the 126 spaces in the inner row. Similarly the year ordinals from 101 to 200 are applied in the next circular row, beginning with 101 on the next sector to the right of the ordinal 100. Also similarly the year ordinals from 201 to 300 are applied in the third row, and the year ordinals from 301 to 400 are applied in the fourth or outside row, always continuing around in a clockwise direction from ordinal 1 to ordinal 400 and with a blank sector only in front of each leap year ordinal. It is to be noted that the Gregorian calendar provides that all years divisible by 4 shall be leap years excepting years divisible by 100 but not by 400. Therefore years 100, 200 and 300 will not be leap years and will not be immediately preceded by a blank sector, but year 400 will be a leap year and hence will be preceded by a blank sector.

Now the front disk *B* is pivotally mounted coaxially upon the rear disk *A*, as in Fig. 2, and the arcuate hole *K* cut away to expose seven mutually adjacent radial columns of days of the month ordinals on disk *A* (see Fig. 4). The problem of locating the month indexes on disk *B* so that, when the desired month index is set in registration with the desired year ordinal on disk *A*, the hole *K* will expose the correct monthly calendar is solved in exactly the same way as heretofore described for the modification shown in Figs. 1 and 2. That is, some modern date is used as a starting point, for instance January 1, 1922, which it is known fell on Sunday. But since the calendar repeats

itself every 400 years the ordinal 322 stands also for the years 722, 1122, 1522, 1922, 2322, etc. Therefore the ordinal 322 can be used for properly locating the hole M and month indexes on disk B in exactly the same way as the ordinal 1922 was used as described hereinabove in the calendar of Figs. 1 and 2. It will be noted that the twelve normal month indexes and the special indexes for January and February appear in Fig. 4 in the same relative positions as they do in Fig. 2. In Fig. 4 Roman ordinals of the months are used for the normal indexes and Arabic ordinals are used for the special indexes for January and February in order to make a clear distinction between them in the drawings. In this calendar it is preferred to print the leap year ordinals on disk A and the special indexes on disk B in a color different from that of the remaining ordinals and indexes to clearly suggest when the special indexes should be used. This perpetual calendar is used in the same way as the first described calendar, with the instruction to the user to first subtract 400 or a multiple of 400 from the year desired and use the resultant remainder as the year ordinal appearing on disk A.

With such a perpetual calendar one can find out in only several seconds on what day of the week his own birthday or any important historical event occurred. For instance, the setting of the disks A and B shown in Fig. 4 disclose that July 4, 1776 fell on Thursday. It is believed such a calendar will be very useful in certain businesses where calendars for past and future months must be frequently consulted, as it will be much quicker and simpler to set this calendar for the month desired than it will be to search among other forms of calendars.

While the form of embodiment of the present invention as herein disclosed, constitutes a preferred form, it is to be understood that other forms might be adopted, all coming within the scope of the claims which follow.

What is claimed is as follows:

1. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and also having a portion cut out exposing a plurality of the year ordinals in
- said ring, and indexes identifying the twelve calendar months arranged each thereupon so as to be registerable with any one of said year ordinals and individually located in such relative position with said cut out sector that when the index for a certain month is set opposite a certain year ordinal the exposed calendar month will be correct for said certain month and year. 70
2. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located in such relative position to said cut out sector that when the index for a certain month is turned to a position corresponding to a certain year ordinal on the rear disk the exposed calendar month will be correct for said certain month and year except for the months of January and February in leap years. 80
  3. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located in such relative position to said cut out sector that when the index for a certain month is turned to a position corresponding to a certain year ordinal on the rear disk the exposed calendar month will be correct for said certain month and year except for the months of January and February in leap years. 90
  4. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located in such relative position to said cut out sector that when the index for a certain month is turned to a position corresponding to a certain year ordinal on the rear disk the exposed calendar month will be correct for said certain month and year except for the months of January and February in leap years. 100
  5. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located in such relative position to said cut out sector that when the index for a certain month is turned to a position corresponding to a certain year ordinal on the rear disk the exposed calendar month will be correct for said certain month and year except for the months of January and February in leap years. 110
  6. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located in such relative position to said cut out sector that when the index for a certain month is turned to a position corresponding to a certain year ordinal on the rear disk the exposed calendar month will be correct for said certain month and year except for the months of January and February in leap years, and additional special indexes for January and February to be similarly used only in leap years. 120
  7. A multiple year calendar comprising: a disk having the ordinals of a number of years arranged in numerical order in a ring but with blank spaces preceding leap years, radial lines dividing said disk into sectors corresponding to said year ordinals, a series of ordinals for days of a month circularly spaced according to said sectors and arranged spirally upon said disk in such manner that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located in such relative position to said cut out sector that when the index for a certain month is turned to a position corresponding to a certain year ordinal on the rear disk the exposed calendar month will be correct for said certain month and year except for the months of January and February in leap years, and additional special indexes for January and February to be similarly used only in leap years. 130

4. A multiple year calendar comprising: a disk having the ordinals of a number of years arranged in numerical order in a ring but with blank spaces preceding leap years, 5 radial lines dividing said disk into sectors corresponding to said year ordinals, a series of ordinals for days of a month circularly spaced according to said sectors and arranged spirally upon said disk in such manner 10 that any seven adjacent sectors will properly represent a calendar month divided into weeks, and a second disk arranged coaxially with said first disk and rotatable thereupon, said second disk having a sector cut out exposing a calendar month on the first disk, and having indexes identifying the twelve calendar months each arranged thereon so as to be registerable with any one of said year ordinals and individually located 15 in such relative position to said cut out sector that when the index for a certain month is turned to a position corresponding to a certain year ordinal on the rear disk the exposed calendar month will be correct for said certain month and year except for the months of January and February in leap years, and additional special indexes for 20 January and February to be similarly used only in leap years.
5. A multiple year calendar comprising: two disks rotatably mounted upon each other, the rear disk being divided into a number of sectors by radial lines and having a series of numerals from 1 to 31 arranged spirally around said disks and spaced according to said sectors, and also having ordinals 25 of certain years spaced in a peripheral direction according to said sectors, the front disk having a portion cut away to expose the numerals on seven adjacent sectors on said rear disk which numerals will represent a calendar month divided into weeks and beginning on any day of the week dependent on the relative setting of said two disks, said front disk also having identifying indexes for the twelve calendar months each arranged thereon so as to be registerable with any one of said year ordinals and individually located 30 in such relative position to said cut away portion that when the index for a certain month is turned to a position corresponding to a certain year ordinal on said rear disk the exposed calendar month will be correct for said certain month and year except only for the months of January and February in leap years, and additional special indexes for 35 January and February to be similarly used only in leap years, said special indexes and the ordinals of the leap years being correspondingly marked to suggest their use at the proper time.
6. A multiple year calendar comprising: two disks rotatably mounted upon each other, the rear disk being divided into a number of sectors by radial lines and having a series of numerals from 1 to 31 arranged spirally 40 around said disk and spaced according to said sectors, and also having ordinals of certain years spaced in a peripheral direction according to said sectors, the front disk having a portion cut away to expose the numerals on seven adjacent sectors on said rear disk which numerals will represent a calendar month divided into weeks and beginning on any day of the week dependent on the relative setting of said two disks, said front disk also having identifying indexes for the twelve calendar months each arranged thereon so as to be registerable with any one of said year ordinals and individually located 45 in such relative position to said cutaway portion that when the index for a certain month is turned to a position corresponding to a certain year ordinal on said rear disk the exposed calendar month will be correct for said certain month and year except only for the months of January and February in leap years, and additional special indexes for 50 January and February to be similarly used only in leap years, said special indexes and the ordinals of the leap years being correspondingly marked to suggest their use at the proper time.
7. A multiple year calendar comprising: two disks rotatably mounted upon each other, the rear disk being divided into a large number of radial sectors and having year ordinals from 1 to 400 spaced by said sectors peripherally around said disk but with a blank space immediately preceding each leap year ordinal, said rear disk also having a series of numerals from 1 to 31 circularly spaced according to said sectors and ar- 55

- ranged spirally upon said disk in such manner that seven adjacent sectors will properly represent a calendar month divided into weeks, said front disk having a portion cut away to expose the ordinals for a calendar month on said rear disk, and also having identifying indexes for the twelve calendar months each arranged thereon so as to be registerable with any one of said year ordinals and individually located in such relative position to said cut away portion that when the index of a certain month is turned to a position corresponding to a certain year ordinal on said rear disk the exposed calendar month will begin on the correct day of the week for said certain month and year except only for the months of January and February in leap years.
20. 9. A perpetual calendar comprising: two disks rotatably mounted upon each other, the rear disk being divided into a large number of radial sectors and having year ordinals from 1 to 400 spaced by said sectors peripherally around said disk but with a blank space immediately preceding each leap year ordinal, said rear disk also having a series of numerals from 1 to 31 circularly spaced according to said sectors and arranged spirally upon said disk in such manner that seven adjacent sectors will properly represent a calendar month divided into weeks, said front disk having a portion cut away to expose the ordinals for a calendar month on said rear disk, and also having identifying indexes for the twelve calendar months each arranged thereon so as to be registerable with any one of said year ordinals and individually located in such relative position to said cut away portion that when the index of a certain month is turned to a position corresponding to a certain year ordinal on said rear disk the exposed calendar month will begin on the correct day of the week for said certain month and year except only for the months of January and February in leap years, and additional special indexes for January and February properly positioned relative to said ordinary indexes to be similarly used only in leap years.
25. 10. A perpetual calendar comprising: two disks rotatably mounted upon each other, the rear disk being divided into a large number of radial sectors and having year ordinals from 1 to 400 spaced by said sectors peripherally around said disk but with a blank space immediately preceding each leap year ordinal, said rear disk also having a series of numerals from 1 to 31 circularly spaced according to said sectors and arranged spirally upon said disk in such manner that seven adjacent sectors will properly represent a calendar month divided into weeks, said front disk having a portion cut away to expose the ordinals for a calendar month on said rear disk, and also having identifying indexes for the twelve calendar months each arranged thereon so as to be registerable with any one of said year ordinals and individually located in such relative position to said cut away portion that when the index of a certain month is turned to a position corresponding to a certain year ordinal on said rear disk the exposed calendar month will begin on the correct day of the week for said certain month and year except only for the months of January and February in leap years, and additional special indexes for January and February properly positioned relative to said ordinary indexes to be similarly used only in leap years, said special indexes and the ordinals of the leap years having distinguishing marks to suggest their relation.
30. In testimony whereof I hereto affix my signature.
35. 40.

HENRY NOGRADY.
